His Attorney.

UNITED STATES PATENT OFFICE

WILLIAM K. RANKIN, OF SCOTIA, NEW YORK, ASSIGNOR TO GENERAL ELECTRIC COMPANY, A CORPORATION OF NEW YORK

ELECTRIC SWITCH MECHANISM

Application filed March 25, 1927. Serial No. 178,427.

My invention relates to electric switch mechanism and particularly to that type of switch mechanism which is especially adapted for the control of modern commercial power circuits of large capacity and which comprises a plurality of similar switches adapted for simultaneous operation and provided with individual operating mechanisms.

Switch mechanism of the type referred to, for example, three-phase switch mechanism, has commonly been constructed with mechanical operating connections between the separate phase switch units, which connections had the effect of insuring simultaneous and equal movements of the moving contacts of the several switch units. Where individual operating mechanisms without mechanical interconnections are employed for the several switch units, there is the danger that, from one cause or another, the several operating mechanisms may not cause their respective switch units to close at the same time, or one or more of the units may even fail to be closed at all. There is also the added danger, in the event of one switch unit failing to close, of the mechanism maintaining the other switch units closed and thereby continuing an unbalanced condition on the circuits controlled by the switch mechanism. It is an object of my invention, therefore, to provide an improved switch mechanism which will to a large degree, if not entirely, avoid the dangers mentioned above, together with other advantages which will appear from the description which follows.

Briefly, in accordance with my invention, I employ a plurality of separate switch units, each having its own separate operating mechanism, and associated with the several operating mechanisms I provide means which automatically becomes effective to render the operating mechanism inoperative in the event that the several mechanisms fail to keep together in their closing movement or that one or more mechanisms fail to start. I also provide means for operating the unlatching or tripping means of the several switch units after a predetermined time interval in the event that any switch unit fails to become latched in closed circuit position.

My invention will be better understood from the following description taken in connection with the accompanying drawing, and its scope will be pointed out in the appended claims.

Referring to the drawing, Fig. 1 is a diagrammatic view of apparatus and circuit connections illustrating one embodiment of my invention; and Fig. 2 is a detail.

In the drawing, I have shown at 1, 2 and 3 parts of three similar switch units, each having an operating rod 4 and each having a separate operating mechanism 5. The switch units 1, 2, 3 may, for example, be phase switches of a three-phase switch installation, and the installation also may be of the isolated-phase type, in which case the several units and their mechanisms would be spaced or suitably isolated from one another. While I have illustrated the units as arranged horizontally, it will be understood that they may be arranged vertically if desired, or in any other manner that may be found desirable. The particular type of switch unit which I have chosen to illustrate is similar to that disclosed in Letters Patent 1,133,032, Jacobs, March 23, 1915, the movable contacts of which are carried by the operating rods 4, and are given a downward movement to close the switch and an upward movement to open the same.

The several operating mechanisms 5 are identical in construction and operation; hence, but one will be described in detail, this one being representative of all three illustrated. The link and lever mechanism 7 for producing a straight line movement of the operating rod 4 may be constructed in any well-known manner, the particular arrangement being immaterial in the present example, and is shown as operated by the crank 8 on shaft 9. The shaft, which in the open circuit position of the switch has its crank 8 standing upright, is given a rotary movement of approximately one half turn by the energization of the solenoid 10 whose plunger 11 is connected with the shaft through the gear 12 and rack 13. Also mounted on shaft 9 is the cam 14 having a concentric face which terminates at one end in the shoulder 15.

The cam 14 and cooperating arm 16 pivoted at 17 constitute the means for latching-in the switch in closed circuit position, the arm being provided with a shoulder 18 which when the mechanism reaches closed circuit 5 position drops over the shoulder 15 of the cam and retains the mechanism. The free end of the arm 16 is shown having an extension 19 terminating in switch contacts 20 which engage one or the other of the opposed 10 fixed contacts 21 and 22, which contacts are arranged in pairs. For raising the arm 16 to release the latch and to allow the switch to open, I have provided the solenoid or trip 15 coil 23 and the cooperating plunger 24, an extension of which forms a hook 25 to engage beneath and to raise the arm 16. Carried also by the plunger 24 is a cross member having contacts which disengage the fixed contacts 26 20 when the plunger is raised. Coil spring 28 serves to return the shaft to its open circuit position. Mounted on the shaft 9 is the circuit controller 30 comprising a drum having a double set of contact plates on its face, as 25 shown more distinctly in Fig. 2. Each set of contact plates comprises a long plate 31 connected to the shorter plates 32, 33 and 34. Of these plates, plate 32 is shown very short for a reason to be explained later. Brushes 30 35, shown for convenience as arrows, are arranged in a row to bear against the cylinder so as to contact with their respective plates as the drum rotates.

The main contactor 37 with which the closing solenoids 10 are connected in series is 35 moved to closed position by the solenoid 38 and in circuit with the solenoid is the winding of the time delay relay 39, the thermal cut-out 40 and the manual switch 41. The latter is 40 shown as of the pull-button type having the movable contact 42 which when the switch is operated is drawn first between the pivoted contacts 43 to close the circuit of solenoid 38 and then by its continued movement is released from contacts 43 and is drawn between 45 contacts 44 in the sealing-in circuit including the contactor 37. Contacts 43 are covered with insulation on their rear faces so that when contact 42 is allowed to return, the circuit through solenoid 38 having been interrupted will not be reclosed. The hand trip 47, the overload trip 48 and the time delay relay 39 are arranged in parallel, any one of which 50 closes the circuit of the trip coils 23. Suitable green and red signal lamps G and R are 55 shown connected in the control circuit so as to be illuminated respectively when the main switch is in open position, as illustrated, and in closed position.

With the parts in the position illustrated, 60 to close the switch units 1, 2 and 3 the pull switch 41 is operated, drawing the contact 42 through the contacts 43 into engagement with the contacts 44. The circuit of solenoid 38 is thus closed, being completed 65 through the winding of the time delay relay 39, the contacts 32 and 31 of the controllers 30 in series and contacts 20, 22 of the several operating mechanisms in parallel. Closing of the contactor 37 causes the energization of 70 each of the switch closing solenoids 10. The shafts 9 are rotated thereby simultaneously for approximately 180 degrees, and through the mechanisms 7 the respective switches 1, 2 and 3 are closed. If the three mechanisms 75 start movement together and continue to keep together, the controller contacts 32, 33 and 34 of the several controllers will make corresponding and simultaneous changes in the circuit connections at the several controllers, and the circuit of solenoid 38 will remain closed. If, however, one of the mechanisms should fail to start with the rest, its short contact 32 would still be in a position 80 to engage a corresponding fixed contact 35, while the controller of another mechanism would have advanced so as to bring the next contact 33 into engagement with a corresponding fixed contact, thus interrupting the circuit of solenoid 38 and allowing the contactor to open. The operating solenoids 10 being deenergized, the switches return to their original position, the presence of the green light G and the absence of the red light R indicating to the operator that for 85 some reason the switch has failed to close. In a similar manner if the several mechanisms having started off together fail to keep together in their closing movement, the controller contacts 33 and 34 will not pass under the fixed contacts simultaneously at the several mechanisms and thus will interrupt the circuit of the solenoid 38. For convenience in the disclosure I have shown the controllers having but three segment contacts 32, 33 and 34, but it will be understood that a greater number may be used if desired. As each switch mechanism reaches its closed circuit 90 it is latched in by the arm 16 dropping over the shoulder 15 of the cam 14. This movement separates contacts 20 and 22. Since these contacts of the several mechanisms are connected in parallel to the circuit of solenoid 38, the solenoid will be open-circuited when and only when all three mechanisms have 95 been latched closed. If for example one mechanism fails to operate its switch sufficiently far to become latched in, the contactor 37 will remain closed until the switch 41 is released or the time delay relay 39 operates to close the circuit of the trip coils 23 whereby all three of the switch operating mechanisms are tripped to open-circuit position. Tripping of the mechanisms is also produced by the operation of the overload responsive device 48 or by the hand switch 47, and signal lamps G and R are lighted respectively when the mechanisms are in the 100 open-circuit position illustrated and in latched-in closed-circuit position, the latter 105 110 115 120 125 130

lamp being controlled by the contacts 20 and 21.

If desired, the controller contacts 32, 33 and 34 may overlap slightly to allow slight 5 permissible differences in the relative positions of the mechanisms without causing the deenergization of the closing solenoids. I prefer, however, to construct the contactor solenoid 38 so as to have a time lag such that 10 the contactor will open only when the above-mentioned permissible difference is exceeded.

I have chosen the particular embodiment described above as illustrative of my invention, and it will be apparent that various 15 modifications may be made without departing from the spirit and scope of my invention, which modifications I aim to cover by the appended claims.

What I claim as new, and desire to secure 20 by Letters Patent of the United States, is:

1. An electric switch comprising a plurality of switch units, each arranged to control a separate main circuit conductor, similar individual operating mechanisms for said 25 units adapted simultaneously to operate the same, and means cooperatively related to said mechanisms and operative in response to the failure of said mechanisms to move together for rendering all of the mechanisms 30 inoperative.

2. An electric switch comprising a plurality of similar switch units, separate operating mechanisms for moving the respective switch units to closed-circuit position, separate latching-in means for holding the respective mechanisms in closed-circuit position, means for releasing the latching-in 35 means, and means including a time delay device for causing the operation of the releasing means if less than the full member 40 of mechanisms are latched in.

3. A switch for a polyphase system comprising separate switch units for controlling the individual phases of said system, a separate 45 operating mechanism for each unit, each mechanism having a plurality of pairs of relatively movable contacts arranged during the closing movement of the mechanisms to successively close a plurality of circuits, and 50 means responsive to the simultaneous closing of corresponding circuits at the several mechanisms for controlling the closing movement of all of the mechanisms.

4. A switch for a polyphase system comprising separate switch units for controlling the individual phases of said system, a separate electric operating mechanism for each unit, a common supply circuit therefor, a circuit controller drum associated with each 55 mechanism and rotated thereby, a plurality of brushes engaging each drum, connections between the brushes of the respective drums whereby a continuous current flow is maintained through a plurality of successive series circuits in response to substantially equal 60

rotative movements of the several drums, and means for interrupting said common supply circuit in response to an interruption in said current flow resulting from an unequal movement of said drums.

5. A switch for a polyphase system comprising a plurality of switch units arranged to control the individual phases of said system, separate electrically energized operating means for each unit, said means being adapted 70 to operate in unison, and means for causing the deenergization of all of said operating means in response to unequal movements of said operating means.

6. A switch for a polyphase system comprising a plurality of switch units for controlling the individual phases of said system, separate operating mechanisms for the respective units, electrical means for moving the operating mechanisms in unison, and 80 means responsive to a difference in the initial movements of the several mechanisms for causing the deenergization of said electrical means.

7. A switch for a polyphase system comprising a plurality of similar switch units for controlling the individual phases of said system, separate mechanisms for operating the respective units, electromagnetic actuating means for producing synchronous movements of said mechanisms, and circuit controlling means responsive to a lack of synchronism in the movements of the mechanisms for deenergizing the actuating means.

In witness whereof, I have hereunto set 90 my hand this 24th day of March, 1927.

WILLIAM K. RANKIN.
